UNITED STATES PATENT OFFICE

ERNEST A. WARD, OF HIGGINSVILLE, MISSOURI

SPRAY GUN AND CLEANING MEANS THEREFOR

Application filed February 11, 1929. Serial No. 339,156.

This invention relates to an improved contribution to the art which embodies, in one instance, a unique portable spray gun for use in otherwise inaccessible places; and further, to novel cleaning means such as may be used in association with a conventional type of gun without requiring alterations of the stock parts.

Spray guns used in applying paints, varnishes, lacquers, etc., are all much of the same construction as the gun herein shown. They are in very general use and their use is rapidly increasing. So far as we know no satisfactory method of cleaning the guns and material lines is now in use or patented, except the present method of taking the guns apart, washing the parts in a cleaning fluid and swabbing out the passages. The material lines are cleaned by flowing the cleaning fluid through them. These methods are unsatisfactory, slow and tedious, and necessitate the use of a considerable amount of cleaning fluid and much time is lost. By the use of the cleaning device herewith presented, the work can be done in a highly satisfactory manner with a minimum amount of fluid and in a fractional part of the time now necessary. Under present methods the cleaning of the gun and material line is too often neglected because of the time and trouble involved in the operation, and although the material may not always harden and clog the gun or material line, skims are formed by the material which are blown on the surface of application when the gun is next put in operation.

Broadly stated, the improved cleaning means is operable either by air pressure from a storage tank or pressure pump, or by air pressure acting on a body of cleaning fluid.

In carrying out the invention I provide a portable closed container which is detachably connected to the distributing head of a conventional bored casting forming a part of the gun, and in its broadest aspect, when using air pressure, without a cleaning fluid, this container functions as an air collection and compression vessel, causing the air when compressed sufficiently, to return or blow

back through the material passage and line for cleaning these parts.

It is further within the inventive concept of the invention to provide a container which may be used in an inverted position 55 or an upright position, and which is intended to contain a cleaning fluid, which when acted upon by the air pressure, is returned through the material passage and line for more effectively cleansing the surfaces of 60 these features.

Then too, it is an object to utilize a cleaning fluid in association with the container not only for cleaning purposes, but of such texture as to further function as a reducer 65 and thinner for the coating material.

It is to be further stated that the invention contemplates the provision of a standardized container, or a container having a standardized connecting neck for accommodating a collar-like coupling for cleaning purposes, as well as a reducer-coupling for portable spray gun purposes. 70

Other features and advantages of the invention will become more readily apparent 75 from the following description and drawings.

In the drawings:

Figure 1 is a view in section and elevation showing a conventional spray gun with the container coupled to the distributing head thereof, the container being shown in an inverted position, this being the more simple form or embodiment of the invention. 80

Figure 2 is a view similar to Figure 1 85 showing the container in an upright position and showing a supplemental fitting used in association therewith, which is necessary for elevation of the cleaning fluid in this arrangement. 90

Figure 3 is a horizontal sectional view taken approximately upon the plane of the line 3-3 of Figure 2 looking downwardly in the direction of the arrow.

Figure 4 is a view taken substantially on 95 the plane of the same line (3-3) looking upwardly.

Figure 5 is a reduced view in elevation and section showing the manner in which the container is adapted for supplying coat. 100

ing material, to provide a small portable spray gun.

It is understood that no claim is made for the construction of the spray gun except as it is combined or used in conjunction with the supplemental appliances of this invention. However, the complete spray gun has been shown with such essential parts in detail in order that a clear comprehension of the invention may be obtained. In all forms of the invention seen, the spray gun is of the pistol type and includes (see Figure 5) a hand grip 6, a pressure air line 7 connected thereto, and the customary right angularly extending bored casting 8. The distributing head is designated by the numeral 9 and carries a retaining cap 10 for the distributing nozzle 11. I have shown a pivoted trigger 12 acting on the air valve trip 13 and a sliding bail 14 acting on the adjustable device 15 on the end of the material control needle valve 16. This valve cooperates with the customary conical fitting 17 associated with the nozzle. The numeral 18 designates a connection for the coating material conducting hose or line 19. When using the cleaning device, the cap 10 and nozzle 11 are removed. When using the device seen in Figure 5 however these parts are left in place as is usual.

Before discussing the different embodiments of the invention in detail, I wish to emphasize the utilization of certain standardized parts and the use of a bottle shaped container which is of a convertible nature and useable in all three of the embodiments of the invention herein represented.

Attention is, however, first invited to Figure 1 wherein it will be seen that I have represented a structure for cleaning the parts 16, 17, 18 and 19. In accomplishing this result I employ, as before intimated, a comparatively small bottle-shaped container 20 which in accordance with this particular embodiment of the invention is used in an inverted position. This is adapted to be partly filled with a cleaning fluid 21. This fluid is preferably of a texture so that it may have the additional function of a thinner for coating material. The reference character 22 designates an air space. The numeral 23 denotes a removable plug which serves a purpose to be hereinafter described. The neck of the bottle is designated at 24 and is internally screw-threaded. In carrying out this idea I have adopted a coupling collar 25 which is internally screw-threaded to permit it to be connected with the aforesaid distributing head 9. This makes it necessary of course to remove the cap 10 and nozzle 11 to substitute the coupling collar. The collar is formed with a flat faced portion 26 forming a wrench grip to facilitate application and removal. Moreover it has

a nipple 27 to thread into the neck 24. This nipple is reduced to form a shoulder at 28 which abuts the end of the neck and forms a fluid-tight joint. If necessary packing rings may be employed to guard against accidental leakage.

Assuming that the parts are arranged as in Figure 1 and a cleaning fluid 21 is in the container 20 it will be seen that when the trigger 12 is depressed it will first open the air line control valve by way of the stem 13 thus shooting a current of air into the container through the cleansing fluid or liquid. This air will be compressed in the space 22 and build up sufficient pressure to forcibly eject the cleansing fluid 21. A successive movement of the trigger 12 in the same direction will then open the needle valve 16 and the fluid under pressure will pass through the fitting 17 and through the passage and the neck 18 into the hose or line 19 thus cleaning the surfaces of these parts.

The greater the pressure in the compression tank the stronger will be the flow of the cleaning liquid when the air valve is opened to full capacity. The air pressure can be regulated by the pull on the trigger. Approximately the same pressure as is carried in the compression tank can be applied in the cleaning of the gun and material line. It is advisable to disconnect the material line from the supply tank (not shown) when the material line is being cleaned to prevent a slight back pressure from the tank, but that is not absolutely necessary since the pressure carried in the air compression tank is strong enough to force the cleaning liquid out of the cleaning device through the gun and material line and into the tank. Since the cleaning fluid used is also used as a reducer or thinner the addition of the small amount of cleaning liquid necessary to clean the gun and material line, will do no harm, especially when it is necessary to add the reducer or thinner which often must be done. For best results the material line should be disconnected from the material tank.

The cleaning device may be used in an upright position, if the inverted position is found unhandy and objectionable. To do this it is only necessary to invert the parts from the position seen in Figure 1 to the position seen in Figure 2. Incidentally, like reference characters designate like parts in Figures 1, 2, 3, 4 and 5. When using the structure as seen in Figure 2 however it is necessary to provide an additional fitting. This comprises a disk-like plug 29 which is threaded into the collar 25 and provided with diametrically opposite openings 30 and centrally arranged fluid elevating tube 31. This tube extends down through the fluid and terminates in a point in close spaced proximity to the bottom of the container 20.

Hence, in this arrangement when the air is turned on, the current of air shoots down through the ports 30 and forces downwardly on the column of liquid, thus forcing it up through the elevating tube, through the parts 17, 18 and 19.

The cleaning device may also be used without cleaning fluid. By attaching the empty cleaning device to the gun and by opening the air valve the air pressure can be forced through the gun, through the material nozzle by opening it, and through the gun and material line thereby forcing accumulated material or obstructions from the gun and material line. In this way too, air pressure may be put into the material tank to quicken the flow of the material.

If desired the cleaning device may be used to force a reducing liquid or thinner into the material tank and in the same operation mix the reducer or thinner with the material. This can be done by putting the reducer or thinning liquid in the cleaning device then by attaching the same to the gun and inverting the cleaning device and by opening the air valve and the material nozzle the reducer or thinning liquid is forced out of the cleaning device into the material tank. Since this reducer or thinning liquid enters the bottom of the material tank the air pressure causes a thorough mixing of the reducer and material.

Coming now to Figure 5 it will be seen that the structure here represented provides a portable arrangement operating somewhat as an ordinary atomizer but using the same bottle-like container 20. In accomplishing this result, the material or fluid line 19 is of course detached and a reducer coupling 33 is substituted therefor. The upper end 34 is coupled to the part 18 and the portion 35 is threaded into the container neck. This portion 35 carries a fluid elevating tube 36 through which the fluid is elevated by suction. In this arrangement the aforesaid screw plug 23 is removed to provide a vent and to prevent the formation of vacuum in the container. With this arrangement it is obvious that when the air is turned on the suction thus produced at the nozzle 11 will elevate the fluid and produce a desired spray.

If it is desired to introduce compressed air into the container 20 to facilitate the flow of material therefrom when used as shown in Figure 5, that may be accomplished by leaving the plug 23 in place, partly unscrewing the cap 10, holding the finger over the outlet ports of fitting 17 and nozzle 11, and opening the valve 16. When this is done, the air will pass into the space between the head 9 and nozzle 11, flowing therefrom through fitting 17 and parts 33 and 36 into the container 20.

A careful consideration of the description in conjunction with the drawings will enable the reader to obtain a clear understanding of the construction, the valuable utility of the bottle-like container, and the utility and standardization of parts necessary in successfully accomplishing the several results described. In fact, it is believed that a clear understanding of the features and advantages will be had and therefore, a more lengthy description is regarded unnecessary.

Minor changes in shape, size and rearrangement of details coming within the field of invention claimed may be resorted to in actual practice if desired.

What I claim is:

1. In a spray gun having a distributing head and air and liquid passages opening through said head, successively operable valve means for controlling said passages, air and liquid lines connected with the intake ends of said passages, means for cleaning the spray gun consisting of a closed container detachably connected with said head and adapted to contain a solution, whereby when said passages are opened, the air will pass through the liquid in the container and force the liquid from the container back through the liquid passage and liquid line connected therewith.

2. In a structure of the class described, a container, an attaching collar removably connected to said container and internally screw-threaded for detachable connection with the distributing head of a spray gun, and a fitting associated with said collar and comprising a disk-like apertured plug threaded into said collar and having a depending liquid elevating tube connected thereto and extending down into the container with its intake end disposed in close spaced proximity to the bottom of the container.

3. In a structure of the class described, a container, an attaching collar removably connected to said container and internally screw-threaded for detachable connection with the distributing head of a spray gun, and a fitting associated with said collar and comprising a disk-like apertured plug threaded into said collar and having a depending liquid elevating tube connected thereto and extending down into the container with its intake end disposed in close spaced proximity to the bottom of the container, together with a spray gun including a screw-threaded distributing head with which said collar is connected.

4. A process for cleaning spray guns having a distributing head and air and liquid passages opening through said head, consisting of attaching a receptacle for cleaning fluid to said distributing head, and providing means to utilize the compressed air

supplied to the gun for forcing the cleaning fluid from said receptacle through the liquid passages of the spray gun in a direction reverse to that in which material is normally forced through the gun for spraying.

In testimony whereof I affix my signature.
